UNITED STATES PATENT OFFICE.

GEORGE V. MARTIN, OF CLEVELAND, OHIO, ASSIGNOR TO THE NATIONAL MALLEABLE CASTINGS COMPANY, OF CLEVELAND, OHIO, A CORPORATION OF OHIO.

POCKET FOR ENGINE-COUPLEDGS.

1,274,737.

Specification of Letters Patent.

Patented Aug. 6, 1918.

Application filed October 14, 1914. Serial No. 866,574.

To all whom it may concern:

Be it known that I, GEORGE V. MARTIN, a citizen of the United States, residing at Cleveland, Cuyahoga county, Ohio, have invented new and useful Improvements in Pockets for Engine-Couplings, of which the following is a specification, reference being had to the accompanying drawings, in which—

10 Figure 1 is an elevation of a coupler pocket embodying my invention; Fig. 2 is a bottom view thereof; Fig. 3 is a section of the coupler pocket showing the coupler-supporting shelf in tilted position; Fig. 4 is a front elevation thereof, with the coupler removed; Figs. 5 and 6 are details of the supporting shelf; Fig. 7 shows the base plate in inverted position, and Fig. 8 is a section showing a modified form of my invention.

My invention relates to coupler pockets for engines or tenders, which have an extended floor or shelf adapted to engage and support the coupler head forward of the mouth of the pocket in order to prevent drooping or sagging of the coupler head when in service. My invention consists in providing a supporting shelf which is adjustable, and which can be positioned at varying heights 25 in order to accommodate differently dimensioned coupler heads, and to compensate for wear. My invention further consists in means for removably attaching the supporting shelf to the pocket at different points 30 so that the pocket may be reversed or inverted in order that the coupler may be positioned at different heights without interfering with the proper operation of the parts.

40 Referring to the drawings, A indicates the coupler pocket plate, and B the coupler head. The pocket plate A is provided with the usual recess 2 for the reception of the coupler shank 3. At the top and bottom of the recess 2 are formed lugs or ears 4, 4', through either pair of which a bolt or pin 5 may be passed, to secure the adjustable floor member or shelf 6 to the pocket. The adjustable shelf 6 is pivotally suspended 45 from the pocket A by means of the bolt or pin 5, secured in either of the holes in the lugs 4 or 4', and which passes through the socket 7 of the shelf 6. The shelf 6 has a forward portion 8, having a cylindrical bearing 9 for the under surface 10 of a wear

plate 11. The wear plate 11 is secured on the cylindrical face 9 by a downward projection 12 and a cotter 13. By reason of its detachable connection with the shelf 6, the plate 11, if worn or broken, may be readily 60 replaced. The shelf 6 has also a rearwardly-extending portion 14, which carries the mechanism for adjusting the height of the wearing plate 11, and this mechanism consists of a set screw 15 or other suitable adjusting means, said screw having a threaded engagement in the aperture 16 and a bearing against the under surface 17 of the plate A. As the floor member 6 is tipped up and down by manipulation of the set screw 70 15, to adjust the height of the coupler as it rests on the wear plate 11, the cylindrical bearings 9 and 10 permit the wear plate 11 to remain in a horizontal position, thus giving an extended horizontal contact surface 75 for supporting the coupler head in its proper operative position. The recess 2 is shown as not centrally located in the vertical dimension of the plate A, and as the lugs 4 are spaced farther away from the horizontal center line of the pocket than are the lugs 4', the height of the coupler may be varied 80 by reversing or inverting in its position on the engine the plate A, and by utilizing the lugs 4 for supporting the adjustable shelf 85 6. The coupler may thus be positioned at a lower level than when the shelf 6 is supported from the lugs 4'. The higher position is shown in Figs. 1, 3 and 4, and the lower position is shown in Fig. 7.

In Fig. 8 I have shown a modified form of my device, in which the adjusting mechanism is comprised of the wedge 18 actuated by the adjusting screw 19 and by which the height of the coupler may be adjusted relative to the pocket.

It is obvious that various modifications may be made in the construction which I have described and shown herein, without departing from my invention.

What I claim is:

1. In a coupler pocket, a shelf for supporting a coupler head pivotally secured to the pocket, the rear extension of the shelf carrying means for adjusting the height of the forward end of the shelf, the forward end of the shelf supporting a wear plate adapted to engage the under side of a coupler head.

2. In a coupler pocket, a shelf for sup-

100

porting a coupler head pivotally secured to the pocket and a wear plate seated on the forward end of the shelf adapted to engage the under side of a coupler head, the wear plate being adapted to tilt with the coupler head and to be maintained substantially in a horizontal plane by contact therewith.

3. In a coupler pocket, an adjustable shelf attached to the coupler pocket, and a wear plate seated on the forward end of the shelf,

the wear plate and the forward end of the shelf having coöperating arc-shaped bearings comprising means for maintaining the wear plate in substantially a horizontal plane.

GEORGE V. MARTIN.
